MEANS FOR PORTAGING GUNS

Wilhelm Figge, Dusseldorf, Germany, assignor to
Rheinmetall-Borsig Aktiengesellschaft, Dusseldorf, Germany, a corporation of Germany

Application January 25, 1937, Serial No. 122,304
In Germany March 18, 1936

2 Claims. (Cl. 89—40)

The invention relates to gun mounts adapted to be dismounted to form portable loads, and particularly to mountain guns which are normally drawn by, for instance, a tandem of 5 horses, which pull between the shafts. For moving on narrow mountain paths the guns are dismounted to form portable loads, in order that they may be carried by men or by pack animals.

When so dismounted, the members forming the 10 draft shaft are used as poles carried by men or animals and the parts of the gun and carriage are suspended from these members by means of cords. With this arrangement the loads swing and thus imperil the porters and quickly tire them. In the 15 case of animals too the arrangement is likewise troublesome. When the loads are suspended by cords they hang far down and the poles must be raised unnecessarily high, and as the loads tend to swing to and fro it is extremely difficult 20 to fix them to a pack saddle.

The invention avoids these drawbacks. It renders it possible for the draft shaft or the separable members of the same to be connected rigidly to the individual dismounted parts of the gun 25 for purposes of portage.

With this object in view the parts of the gun mount which are designed to form the separate loads are provided at suitable places with coupling members which are complementary to coupling 30 devices on the individual poles which are employed to connect the draft shaft for normal service. That is to say, the same coupling means are used for fitting the pole in the gun and arranging a pair thereof for normal traction 35 purposes as for portage, when the means serve to couple the poles rigidly to the individual loads. The coupling members are preferably designed as a bayonet joints which are so constructed that a rigid connection is not effected and it is not possible for the load to be lifted before the coupling 40 has been properly engaged and locked.

A typical embodiment of the invention is illustrated in the accompanying drawing in which—

45 Fig. 1 shows a side view of a gun mount with the draft shaft fitted thereto in the normal arrangement for traction.

Fig. 2 is a coupling member in longitudinal section.

50 Fig. 3 shows a front view of the coupling member of Fig. 2.

Fig. 4 shows a complementary coupling member in longitudinal section.

Fig. 5 shows a front view of the member of 55 Fig. 4.

Fig. 6 shows a gun cradle with two coupling members on each side thereof and

Fig. 7 shows the cradle coupled on both sides with the draft shaft members or poles for portage purposes.

The draft shaft which serves for normal traction of the gun mount consists of the rod like members a_1 , a_2 , a_3 , a_4 and the transverse member a_5 which are coupled as a whole with the gun carriage tail. All the individual or pole parts of the 10 draft shaft a_1 to a_5 are provided at the different joints with coupling members b , b_1 which together form a bayonet joint. For locking the members in coupling engagement there are provided spring-urged locking noses b_2 (Fig. 4) on the 15 coupling member b_1 to engage in the groove b_4 which is located in the other coupling member b .

The individual loads of the dismountable gun, for instance the cradle or slide c (Figs. 6 and 7) are provided at suitable locations with coupling 20 members b , with which the poles or members a_1 , a_2 , a_3 and a_4 can be rigidly coupled by means of their complementary coupling member b_1 . It will be seen that after the draft shaft members have been fixed to the cradle, the latter can be 25 carried like a stretcher, or it can be raised quite easily on to the saddle of a pack animal where it can be fixed.

After the members coupled on one side of the cradle have been removed, the cradle while in 30 the pack saddle can be turned or moved so that the toothed elements, which are a hindrance in loading, are always uppermost. When the individual loads are suspended by cords, as was hitherto usual, it was difficult to adjust the loads 35 to the best position on the saddle. The coupling together of the complementary members of the bayonet coupling is facilitated in known manner by a bolt b_3 on the coupling member b which is adapted to enter a hole in the complementary 40 coupling member b_1 (Fig. 2). Now, in order to prevent a bayonet joint which has not been closed, from allowing the load to be suspended solely from the centering pins b_3 , these are designed with round heads. With these heads it 45 is possible to lift the load only if the bayonet joint is at least partially closed.

The individual members of the dismountable limber may also be used as levers to assist in traversing the gun. To effect this one or more 50 complementary coupling members similar to the coupling members on the parts of the gun which form the individual loads are fixed to the trail.

I claim:

1. In a gun mount, a draft shaft for normal 55

traction adapted to be divided in sections, forming carrying-poles, and having complementary coupling members for jointing and disjoining said draft shaft sections, and corresponding coupling members on the gun mount parts for rigidly connecting said parts with the carrying-poles for transporting the individual loads of the dismounted gun mount.

2. In a gun mount, a draft shaft for normal traction adapted to be divided in sections, forming carrying-poles, and having complementary

coupling members for jointing and disjoining said sections, and corresponding coupling members on the gun mount parts for rigidly connecting said parts with the carrying-poles for transporting the individual loads of the dismounted gun mount, said coupling members comprising parts of bayonet joints and having centering means with rounded heads adapted to facilitate the engagement of the coupling members of a joint. 5
